OF DELAWARE.

CONTROLLING MECHANISM FOR LIQUID-DISPENSING APPARATUS.

1,297,801.

Specification of Letters Patent.

Patented Mar. 18, 1919.

Application filed November 12, 1917. Serial No. 201,668.

To all whom it may concern:

Be it known that I, RAYMOND CROWDER, a citizen of the United States, residing at Edgewood, in the county of Allegheny and State of Pennsylvania, have invented certain new and useful Improvements in Controlling Mechanism for Liquid-Dispensing Apparatus, of which the following is a specification.

10 My invention consists of an improvement in controlling mechanism for liquid dispensing apparatus for delivering gasoline or other liquids in measured quantities from a measuring or secondary tank connected with a main reservoir or source of supply.

The improved controlling mechanism herein described is adapted particularly for use with apparatus similar to that described 20 in the patent to George W. MacKenzie, Jr., No. 1,255,763, Feb. 5, 1918, in which the liquid is caused to flow into a transparent measuring tank by the formation of a partial vacuum therein. A central vertically adjustable conduit extends upwardly 25 into the secondary or measuring tank and is connected with a storage vessel or other source of supply. Suitable air exhausting means is provided and adapted to exhaust 30 the air from the secondary tank when desired. The adjustable conduit may be set to predetermined positions by means of a handle secured thereon, and is located in the selected position by engaging a recess 35 in one of a series of adjustable stop members within the pump standard.

The controlling mechanism described herein is then operated, which causes the air suction means to be set in motion, thereby 40 exhausting the air from the secondary tank and creating a partial vacuum.

The principal object of the present invention is to provide a controlling means which will be positive in action and will automatically shut off the atmospheric pressure 45 from the measuring tank when the air exhausting means is set in motion.

A further object is to provide such mechanism which will shut off atmospheric pressure 50 from the tank and start the air ex-

hausting mechanism by one operation, but which will delay the starting of the air exhausting means until the atmospheric pressure has been cut off from the measuring tank.

Another object is to provide a mechanism which will insure at all times when the device is not in motion that the circuit is broken which operates the air exhausting means.

Other and further objects are clearly set forth in the following specification and illustrated in the accompanying drawings in which:

Figure 1 is a side elevation of a complete apparatus having the casing partly broken away to show the invention;

Fig. 2 is a detail view of the pump standard, partly broken away, showing the enclosed mechanism on an enlarged scale;

Fig. 3 is a cross sectional view of the pump standard on the line III, III of Fig. 1;

Fig. 4 is an enlarged detail view of the controlling mechanism detached from the apparatus;

Fig. 5 is a diagrammatic view of a circuit used in the operation of the device; and

Fig. 6 is a vertical sectional view through the measuring tank having the standard broken away.

Referring more particularly to the drawings, the letter A designates a measuring tank which has a cylindrical glass body portion supported upon a hollow casing or support 2.

A vertically adjustable conduit 3 extends upwardly from a storage vessel (not shown) and is adapted to be set at selected levels by the operator.

The secondary or measuring tank A consists of a cylindrical transparent shell 4, clamped between a base 5 and top 5^a by means of a series of rods 5^b, and is provided with an outlet valve 6 adapted to receive a hose or other conduit to convey the liquid to the user.

Conduit 3 is adapted to be raised and lowered, and to be partially rotated, by

means of an operating trigger or handle 7 which is fixed thereon. The handle 7 is adapted to be engaged in recesses 8 in stop members 9 adjustably secured on the tubular member 10.

At its upper end conduit 3 is provided with a splash coping 11 suitably secured thereto, and adapted to deflect the rising liquid downwardly. Conduit 3 is adjustable 10 to different levels to limit the amount of liquid within the tank A. Each recess 8 designates a measuring level and when handle 7 is in place within one of the notches or recesses 8 the upper terminal of 15 conduit 3 will be at a corresponding measuring level. Liquid is drawn through the conduit 3 by creating a partial vacuum within tank A, and when sufficient liquid has entered such tank, atmospheric pressure is 20 established, through a valve 15 to be described, causing all excess liquid above the terminal of the conduit 3 to flow back through the same into the storage vessel from which it has been drawn.

For the purpose of creating a partial 25 vacuum in the tank A, any suitable air exhausting means may be employed as a pump 12 of any well known type and having a driving motor 13.

A suction pipe 14 is connected with the pump 12 and with the upper portion of tank A. Communicating with the pipe 14 is a vertical check valve 15 having a stem 15^a, adapted to open and close the pipe 14 to 35 the atmosphere.

The valve 15 is adapted to be operated by lever-actuating rod 16 provided at its end with a tubular ferrule 17 having longitudinal slots. A valve stem 15^a is adapted to be fitted within such tubular portion and to be held in position by a cross pin 17^a which extends through the slots. A coil spring 18 is mounted within such tubular portion, and provides a cushion bearing 40 for the end of the valve stem 15^a. The rod 16 is provided with a ball shaped gripping member 19 below the tubular portion, adapted to be gripped by the operator to set the mechanism in operation.

Rod 16 has its lower end pivoted to one end of a crank arm lever 20 pivotally mounted on support 21 mounted within casing 2. The other end of the crank arm lever 20 is pivoted to a push rod 22 adapted to engage the positive button 23 of a push switch 24, of well known type having two buttons for operating the same, one for making and one for breaking a circuit.

The negative button 25 is adapted to be 50 engaged by a coil spring 26, at all times. The spring 26 is mounted in a tubular member 27 having a closed end, and is of such tension that the button 25 is always held in open position except when the rod 22 is 55 pressed against the button 23.

It will be readily seen that with the above construction one lifting of the rod 16 will first close the check valve 15, and then complete the circuit through the switch 24 to the motor 13 operating the pump 12, but the 60 particular operation of the rod 16 and its associated parts is of especial importance in a machine of the type involved.

The operator, when desiring to measure a quantity of liquid, will grasp the gripping 75 member 19 and raise the rod 16 which will close the check valve 15. Said valve has only about one fourth inch play and therefore will close almost immediately upon lifting the rod 16, thus cutting off atmospheric 80 pressure to the tank A, and further movement of the rod will tend to compress the spring 18 and to continue to rock the crank arm 20 and force the push rod 22 against the button 23, until the circuit is closed 85 through the switch 24.

Upon being released, rod 16 will automatically return to its lower or open position by gravitation and spring pressure, and the valve 15 will be opened to create atmospheric pressure simultaneously with the breaking of the circuit by means of the tension of the spring 26 upon button 25.

A conduit 30 extends upwardly within the casing 2, through the base 5 and is bent outwardly and upwardly around the tank A and enters the top 5^a to carry electric wiring 31 to the top for a light, if desired.

The general operation of the device is the same as that in the patent to George W. 90 MacKenzie, Jr. referred to in the forepart of this specification and need not be gone into in detail.

What I claim is:

1. A liquid measuring apparatus provided 100 with a measuring vessel, a suction pump having a conduit connected therewith, and provided with a valve-controlled atmospheric inlet, a motor for the pump, and means controlling the operation of the motor 110 having a connection adapted to close the atmospheric inlet prior to and in connection with the starting of the motor.

2. In a liquid measuring apparatus having 115 a measuring vessel, a suction pipe and pump connected therewith, and a pump motor having a circuit controlling switch; a normally open valve-controlled air inlet connection for the suction pipe having a valve lever, lever mechanism connected with the controlling switch, and a lifting rod therefor provided with a gripping device and having a yielding connection with the air inlet valve.

3. In a liquid measuring apparatus having 125 a measuring vessel, a filling conduit connected therewith, an electrically operated air exhaust pump connected with said measuring vessel, a valve adapted to be normally positioned to permit the entrance of atmos- 130

pheric pressure to said vessel, a switch adapted to make and break the electric circuit for operating said pump, and a lever mechanism adapted to close said valve and 5 operate said switch to make a circuit, said switch being adapted to be operated after said valve has been closed.

4. The combination with a liquid measuring and dispensing apparatus having a 10 measuring vessel, a filling conduit connected therewith, an electrically operated air exhaust pump connected with said measuring vessel, and a valve adapted to be normally opened to permit the entrance of atmospheric pressure to said vessel, of a switch of 15 the push button type adapted to make and break the electric circuit for operating said pump, a lever mechanism adapted to close said valve and operate one of the push but 20 tons of said switch to close the circuit to said pump, and means for normally holding the other of said buttons in position to break the circuit to said pump.

5. The combination with a liquid measuring and dispensing apparatus having a 25 measuring vessel, a filling conduit connected therewith, an electrically operated air exhaust pump connected with said measuring vessel, and a valve adapted to be normally 30 opened to permit the entrance of atmospheric pressure to said vessel, of a switch of the push button type adapted to make and break the electric circuit for operating said pump, said switch being normally held in 35 position to break the circuit, and a lever mechanism having a yielding connection with said valve and a positive connection with said switch, said mechanism being adapted to close said valve a predetermined

time before said switch is closed to make 40 said circuit.

6. The combination with a liquid measuring and dispensing apparatus having a measuring vessel, a filling conduit connected therewith, an electrically operated air exhaust pump connected with said measuring vessel, and a valve adapted to be normally opened to permit the entrance of atmospheric pressure to said vessel, of a switch of the push button type adapted to make 45 and break the electric circuit for operating said pump, flexible means coöperating with said switch for normally holding it in open position, and a lever mechanism having a yielding sliding connection with said valve 50 and adapted to operate one of the push buttons of said switch to complete the circuit to said pump when said lever mechanism is operated, said lever mechanism being adapted to close said valve an appreciable time 55 before said switch is operated to make said circuit.

7. In a liquid measuring apparatus having a measuring vessel, a suction pipe and pump connected therewith, and a pump motor having a circuit controlling switch; a normally open valve-controlled air inlet connection for the suction pipe having a valve, operating mechanism for closing and opening the motor controlling switch, and an 70 operating rod connected with said mechanism provided with a gripping device and in telescoping connection with the stem of said air inlet valve with an intervening spring. 75

In testimony whereof I hereunto affix my signature.

RAYMOND CROWDER.
